US00D826201S

(12) **United States Design Patent** (10) Patent No.: **US D826,201 S**
Won et al. (45) Date of Patent: **** Aug. 21, 2018**

(54) **TV RECEIVER**

(71) Applicant: **LG ELECTRONICS INC.**, Seoul (KR)

(72) Inventors: **Hyojin Won**, Seoul (KR); **Hyeyoung Hong**, Seoul (KR); **Yongho Lee**, Seoul (KR); **Youngkyoung Kim**, Seoul (KR); **Sunggu Joe**, Seoul (KR)

(73) Assignee: **LG ELECTRONICS INC.**, Seoul (KR)

(**) Term: **15 Years**

(21) Appl. No.: **35/503,478**

(22) Filed: **Feb. 10, 2017**

(80) **Hague Agreement Data**

Int. Filing Date: **Feb. 10, 2017**

Int. Reg. No.: **DM/094860**

Int. Reg. Date: **Feb. 10, 2017**

Int. Reg. Pub. Date: **Aug. 11, 2017**

(30) **Foreign Application Priority Data**

Aug. 24, 2016 (KR) 30-2016-0041365

(51) **LOC (11) Cl.** **14-03**

(52) **U.S. Cl.**

USPC **D14/126**

(58) **Field of Classification Search**

USPC D14/125-134, 239, 336, 371, 373-377, D14/379-380, 382, 447, 448, 450, 451, D14/452; D21/329, 332; D10/26; D6/300-311, 314

CPC G06F 1/16; G06F 1/1601; G06F 1/1637;

H04N 5/64; H05K 5/0017; H05K 5/0204; H05K 5/0217
